UNITED STATES PATENT OFFICE.

JOHN W. JONES AND JOSEPH HELMER, OF GRAND RAPIDS, MINNESOTA.

NUT-LOCK.

SPECIFICATION forming part of Letters Patent No. 669,838, dated March 12, 1901.

Application filed September 11, 1900. Serial No. 29,679. (No model.)

To all whom it may concern:

Be it known that we, JOHN W. JONES and JOSEPH HELMER, citizens of the United States, residing at Grand Rapids, in the county of Itasca, State of Minnesota, have invented certain new and useful Improvements in Nut-Locks, of which the following is a description, reference being had to the accompanying drawings, and to the letters of reference 10 marked thereon.

Our invention relates to that class of nut-locks in which a flat plate or washer having a hole therein for the passage of the bolt is placed beneath the nut, and being kept from 15 rotation by engagement with the base-plate through which the bolt extends has one or more projecting portions bent up to engage the nut after it has been screwed down to place and prevent its rotation.

20 Our invention consists in the construction and combination of elements hereinafter described and claimed.

In the accompanying drawings, which form a part of this specification, Figure 1 is a plan view, and Fig. 2 is a side view, of one form of our invention. Fig. 3 is a plan view of a modification. Fig. 4 is a side view of the form of our invention shown in Fig. 3. Fig. 5 is a cross-sectional view of the same. Fig. 30 6 is a plan and Fig. 7 a sectional view showing a modification in the means for securing the base-plate against rotation, and Fig. 8 is a plan view of a fish-plate for rail-joints having our invention applied thereto.

35 In the drawings, A is a base-plate through which the bolt B passes and against the upper surface of which the nut C presses.

D is the locking-plate by which the nut is held from rotation.

40 The base-plate A is prevented from rotation in the construction shown in Figs. 1 to 5 by means of projections α on its under side, which enter holes or grooves in the material of the article to be held in place by the bolt.

45 If the article to be held in place is metal, it will be necessary to cut recesses in its face to receive these projections. If the material is wood, the projections will usually be forced into the wood without cutting such recesses.

50 In the form shown in Figs. 6 and 7 the base-plate A is prevented from rotation by means of screws α' , having angular heads α^2 , which

are received in recesses α^3 , cut, preferably, in the edge of the base-plate. In using this form of our invention the screws α' will first 55 be entered in the material of the article to be held in place by the bolt and the base-plate placed over them, with the recesses α^3 engaging the screw-heads.

In case a base-plate having two or more 60 bolts passing therethrough is used, as the fish-plate shown in Fig. 8, the base-plate will be held from rotation by its engagement with the flange and base of the rail, and will be further held from rotation by the several 65 bolts. In the upper face of the base-plate a broad shallow groove A' is cut in which the locking-plate D rests. This groove A' is slightly less in width than the width of the nut C, so that the nut in turning bears upon 70 the upper surface of the base-plate. The edges of the groove A' are undercut at α^4 and the edges of the plate D are correspondingly beveled, so that it will be retained in position when the nut is removed. 75

In the form shown in Figs. 1 and 2 the portions D', which extend beyond the nut C, are made narrow, as shown, and when bent upward to hold the nut from rotation fit into recesses C', cut in opposite edges of the nut, 80 and when forced into place and dressed off give a finished appearance.

In the form shown in Figs. 3 to 5, inclusive, the outer portion of the upper surface of the base-plate is cut away, as shown at 85 α^5 , leaving a central boss on which the nut bears. By thus cutting away the upper surface of the base-plate the portions of the locking-plate D which project beyond the nut are freed from engagement with the undercut edges of the groove A' and may be 90 bent up, as shown, against the edges of the nut to hold it from rotation.

In operation the locking-plate D will be placed in position on the base-plate, and the latter is then placed over the projecting end of the bolt and the nut screwed on. The projecting portions of the plate D are then bent upward against the edges of the nut or into the recesses in its edges, as the case may 100 be, and the nut will then be securely locked from rotation.

While we have shown our locking device applied to square nuts, it will be understood

that it may be applied to nuts having six or any even number of sides.

Having thus described our invention, what we claim, and desire to secure by Letters Patent, is—

1. In a nut-lock, the combination with a base-plate having a groove with undercut edges in its upper face, means for preventing the rotation of the base-plate, a bolt passing through the base-plate and a nut on said bolt, of a locking-plate having beveled edges engaging the undercuts of the groove and having portions thereof projecting beyond the nut adapted to be bent upward to prevent the rotation of the nut; substantially as described.
2. In a nut-lock, the combination with a base-plate having the outer portion of its upper face cut away so as to leave a central boss and having a groove with undercut edges in its upper face, means for preventing the rotation of the base-plate, a bolt passing through the base-plate and a nut on said bolt, of a locking-plate having beveled edges engaging the undercuts of the groove, and having portions thereof projecting beyond the nut adapted to be bent upward to prevent the rotation of the nut; substantially as described.
3. In a nut-lock, the combination with a base-plate having a groove with undercut edges in its upper face, and recesses in its edge, screws having angular heads fitting said

recesses, a bolt passing through the base-plate and a nut on said bolt, of a locking-plate having beveled edges engaging the undercuts of the groove and having portions thereof projecting beyond the nut adapted to be bent upward to prevent the rotation of the nut; substantially as described.

4. In a nut-lock, the combination with a base-plate having a groove with undercut edges in its upper face, means for preventing the rotation of the base-plate, a bolt passing through the base-plate, and a nut on said bolt having recesses in opposite edges, of a locking-plate having beveled edges engaging the undercuts of the groove and having portions thereof projecting beyond the nut and adapted to be bent upward into the recesses in the edges of the nut, and to thus prevent the rotation of the nut; substantially as described.

In testimony whereof we affix our signatures in presence of witnesses.

JOHN W. JONES.
JOSEPH HELMER.
